[57] CLAIM

The ornamental design for a rechargeable air pump, as shown and described.

DESCRIPTION

FIG. 1 is a perspective view of the rechargeable air pump showing my new design;

FIG. 2 is a perspective view in an operational mode of the rechargeable air pump of FIG. 1, an attachment portion which is not part of my new design being shown in broken lines;

FIG. 3 is a front view of the rechargeable air pump of FIG. 1;

FIG. 4 is a side view of the rechargeable air pump of FIG. 3, viewed from the left thereof;

FIG. 5 is a top plan view of the rechargeable air pump of FIG. 3;

FIG. 6 is a rear view of the rechargeable air pump of FIG. 3;

FIG. 7 is a side view of the rechargeable air pump of FIG. 3, viewed from the right thereof; and,

FIG. 8 is a bottom plan view of the rechargeable air pump of FIG. 3.
